PROPELLER LIFT ASSEMBLY

Harvey J. Jacobson, deceased, late of Travis Air Force Base, Calif., by Vinnie M. Jacobson, legal representative, 1123 E. Princeton, Spokane, Wash.

Filed Nov. 28, 1962, Ser. No. 240,764

2 Claims. (Cl. 294—81)

(Granted under Title 35, U.S. Code (1952), sec. 266)

The invention described herein may be manufactured and used by or for the United States Government for governmental purposes without payment to the patentee of any royalty thereon.

This invention relates to a lift assembly for use in installation and removal of propellers.

One object of the invention is to provide a propeller lift assembly which will permit rotation and tilting of the propeller.

This object and other objects will be more fully understood from the following detailed description taken with the drawing wherein:

FIG. 1 shows a perspective view of the device of the invention as it is attached to an aircraft propeller;

FIG. 2 is a front view of support ring and rail attaching plate for the device of FIG. 1;

FIG. 3 is a sectional view of the device of FIG. 2 along the line 3—3;

FIG. 4 is a front view of the extension arms for the device of FIG. 1;

FIG. 5 is a top view of the device of FIG. 4;

FIG. 6 is a front view of the right rail support bearing member for the device of FIG. 1;

FIG. 7 is an end view of the device of FIG. 6;

FIG. 8 is an end view of the left rail support bearing member for the device of FIG. 1;

FIG. 9 is a perspective view of the device of the invention as it is attached to a propeller in the position that the propeller is taken from the aircraft; and,

FIG. 10 is a perspective view of the device of the invention attached to a propeller positioned on a propeller dolly.

In the removal and installation of a propeller on an aircraft, the propeller is held in the Y-position; whereas the propeller as placed on the propeller dolly is in the inverted Y-position. This requires a rotation of 45° from the position in which the propeller is removed from the aircraft to the position in which it is stored on the dolly. Also the propeller must be tilted from the vertical position when it is placed on the dolly. According to this invention, a lift assembly is provided in which a trolley runs on an arcuate rail to provide the 45° rotation of the propeller and the rail is pivoted to the propeller support assembly to permit tilting of the propeller.

Referring now to FIG. 1 of the drawing, reference number 10 refers to the propeller lift assembly of the invention connected between a hoist hook 11 and a standard base plate 12 attached to propeller 13. The support ring 15 is secured to the base plate 12 by means of a standard locking ring 16. The base plate 12 and locking ring 16 are standard equipment and form no part of this invention.

The support ring 15, shown in greater detail in FIGS. 2 and 3, has a flange plate 21 and an interconnecting member 20. The flange plate 21 is attached to the plate 26 of the rail support attaching member 18 by means of four bolts 19, two of which are shown in FIG. 2. The retractable pin 22 engages a positioning groove on the base plate 12 (not shown).

2

The attaching member 18 has two rail support attaching plates 23 and 24 connected by a reinforcing web member 25 and the intermediate plate member 26.

A rail 30 is pivotally supported between two rail support bearing members 31 and 32. The support bearing member 31 is of greater length than member 32 and is connected directly to the plate 23 by means of plate 33 and four bolts 34, (two of which are shown in FIG. 9). So that the rail 30 may be mounted with its center of curvature at the center of gravity of the propeller, an extension arm 36 is connected between plate 24 and the bearing member 32. The extension arm 36 is secured to plate 24 by means of a plate 37 and four bolts 38, three of which are shown in FIG. 1. The flange 40 on the bearing member 32 is connected to the flange 41 on extension arm 36 by means of four bolts 42, two of which are shown in FIG. 1.

A trolley assembly 45, having a trolley wheel 46 riding on rail 30, is supported upon hook 11 by means of a clevis 48.

In the operation of the lift assembly of the invention, the device is attached to the propeller as shown in FIG. 9 with the trolley in the extreme right position on rail 30 and the propeller in the Y-position. For placing on the dolly 50, shown in FIG. 10, it is necessary to rotate the propeller 45° so that the trolley is in the extreme left position on rail 30. The propeller can then be tilted back onto the dolly by means of the pivots at the end of rail 30.

There is thus provided a lift assembly which will permit rotation and tilting of the propeller for storing the propeller on a dolly.

While a certain specific embodiment has been described in detail, it is obvious that numerous changes may be made without departing from the general principle and scope of the invention.

What is claimed is:

1. A propeller lift assembly comprising: a ring support member adapted to fit on a standard propeller base plate, an arcuate rail member, trolley lifting means for supporting said rail and having roller means for engaging the lower surface of said rail, bearing means secured to each end of said rail for permitting rotation of said rail at right angle to the direction of motion of said trolley, and means, connected between said bearing means and said ring support member for supporting said rail with its center of curvature at the center of gravity of the propeller to which it is attached.

2. A propeller lift assembly comprising: a ring support member adapted to fit on a standard propeller base plate, an arcuate rail member, trolley lifting means for supporting said rail and having roller means for engaging the lower surface of said rail, bearing means secured to each end of said rail for permitting rotation of said rail at right angle to the direction of motion of said trolley, a plate member secured to said ring support member, one of said bearing means being directly connected to said plate member, an extension member connected between the other bearing member and said plate member adapted to support said rail with its center of curvature at the center of gravity of the rail to which it is attached.
